UNITED STATES PATENT OFFICE.

EDWARD HANNA FORNEY, OF DENVER, COLORADO.

COLLAPSIBLE DRINKING-CUP.

988,453.

Specification of Letters Patent. Patented Apr. 4, 1911.

Application filed August 28, 1909. Serial No. 515,035.

To all whom it may concern:

Be it known that I, EDWARD HANNA FORNEY, a citizen of the United States, residing at the city and county of Denver and State of Colorado, have invented certain new and useful Improvements in Collapsible Drinking-Cups; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to temporary drinking cups, or those designed to be used but once and afterward thrown away, my object being to provide a collapsible device of this character, composed of such cheap material as to make the foregoing practice inexpensive.

20 My improved cup is so constructed that its bottom is devoid of a supporting area, thus making it impossible for the cup to maintain an upright position, except when supported from the sides, as when held in the hand of the user. It is constructed of some reasonably stiff material which, however, may be folded without breaking and which normally assumes a flat or collapsed position, being maintained in the collapsed form by a wire spring composed of two members applied to the opposite sides of the cup, their extremities protruding beyond the cup and forming bearing parts for the thumb and finger, whose pressure causes the cup to open, when it is desired to use the same. As soon as the pressure is released, the force of the spring acting upon the opposite sides of the cup causes it to collapse immediately.

25 Having briefly outlined my improved construction, I will proceed to describe the same in detail, reference being made to the accompanying drawing in which is illustrated an embodiment thereof.

30 In this drawing: Figure 1 is a plan view of a blank from which my improved cup is made. Fig. 2 is a perspective view of the completed cup, shown open and containing liquid. Fig. 3 is a view of the blank after folding and fastening the two side flaps. Fig. 4 shows the cup after folding and securing the bottom flap. Fig. 5 is a similar view,

showing the spring wire in place, before folding the upper part downwardly to hold the wire. Fig. 6 is a detail view of the wire spring forming a part of the cup.

The same reference characters indicate the same parts in all the views.

35 Referring to Fig. 1, the blank A B C D E from which the cup is formed, is to be cut from some flexible material adapted to fold and bend readily without breaking. It should be sufficiently impervious to water to cause the cup to hold its contents without softening or leakage for a reasonable length of time. Vegetable parchment paper will be suitable for the purpose, though it is evident that the invention is not limited to any particular material. Said blank A B C D forms the shell or wall of the cup when folded along the lines *a* *y* and *b* *y'*, and connected along the edges A C and B D with a suitable glue or cement, as shown in Fig. 3.

40 In Figs. 1 and 3 to 5, inclusive, the diagonal shading indicates the surfaces to which the adhesive substance is to be applied in manufacturing the cup. The lower extremities of the longitudinal folding lines terminate at points *y* *y'* instead of *x* *x'*, and form small triangles *c* *x* *y* and *d* *x'* *y'*, which serve to reinforce the corners made during the next folding act.

45 Fig. 4 is a view of the cup with the wall or shell completed by folding the edge B D over the edge A C, the side flaps 5 being folded on the dotted lines 6, and the bottom flap 7 being folded on the dotted line 8 and fastened along its edges to the wall of the cup, by means of suitable glue or cement to close the bottom of the receptacle.

50 As shown in the drawing, the spring 10, forming a part of my improved device, is composed of two members, having slightly separated parallel parts 12, twisted together at their extremities, as shown at 13, the ends of the members extending beyond the twist and formed into forked bearings 14, against which the thumb and finger of the user bears when opening the cup for filling purposes. The rough extremities of the wire members are turned back upon the protruding portions or bent down thereon, as shown at 15, in order to form a smooth holding or bearing surface.

55 After the spring is formed, as shown in

100

105

Fig. 6, the cup in the form shown in Fig. 4, is passed into the space 16, between the parts 12, the spring being located at the top of the cup and just below the narrow portions 5 17, above the dotted lines 18 in Figs. 3 and 4, these dotted lines being also shown in Fig. 1. The parts 17 are then turned downwardly covering the parts 12 of the spring and are sealed against the opposite walls of the 10 cup, thereby forming pockets for the wire parts 12, whereby the spring 10 is retained in position, as illustrated in Fig. 2.

In opening the cup for filling purposes, it 15 is only necessary for the user to press upon the forked bearing portions of the spring, as illustrated in Fig. 2. This pressure will cause the parts 12 of the spring to bow outwardly, causing the top of the cup to open, giving it an oval shape, or a shape approaching the circular form, depending upon the 20 degree of pressure applied.

It will be noted that one of the objects sought in the construction of this drinking cup is to avoid the use of a bottom, or stand, 25 upon which it might rest. Were it thus provided, it might be left standing near a drinking fountain, or other source of water supply, and thus induce a second use by others. Without any area to rest upon, it 30 must be thrown away.

The object of the spring is to form a reinforcement to hold the cup flat in packages, or in dispensing or vending machines and to stiffen its upper edge and prevent it from 35 kinking when placed against the lips. The spring also serves as a means to hold the top of the cup closed, and to distend, or open it when pressure is applied to its bearing extremity, as heretofore explained.

40 The upper edge of the blank is provided with V-shaped recesses F, to facilitate the operation of folding the parts 17, which form the pockets for retaining the spring in place.

Having thus described my invention, what 45 I claim is:

1. A collapsible cup having a compressible reinforcing spring extending entirely around its mouth to prevent kinking.

2. A temporary drinking cup having a 50 spring composed of two members and an opening between them for the insertion of the cup body, the extremities of the open members being connected and provided with finger rests or pushers.

55 3. A drinking cup whose mouth is equipped with an opening and closing spring composed of two parallel members, the extremities of the two members being twisted together and formed into finger rests, for the 60 purpose set forth.

4. A blank for a drinking-cup composed of an integral piece of material having a central body member, side flaps separated therefrom by longitudinal folding lines 65 whose upper extremities terminate in V-shaped recesses, and a bottom flap separated from the body of the blank by a transverse folding line intersecting the longitudinal lines, and having reinforcing triangular 70 areas extending beyond the intersection of the longitudinal and transverse folding lines, for the purpose set forth.

5. A blank for a drinking-cup, composed of an integral piece of material having a 75 central body member, side flaps, a bottom flap and triangular areas extending beyond the body and flap members and adapted to fold inward at the opposite bottom corners of the cup for reinforcing purposes, substantially as described.

In testimony whereof I affix my signature in presence of two witnesses.

EDWARD HANNA FORNEY.
